UNITED STATES PATENT OFFICE.

EDWIN H. LUDEMAN, OF NEW YORK, N. Y.

STEAM-HEATED PISTON.

1,249,789.

Specification of Letters Patent. Patented Dec. 11, 1917.

Application filed February 8, 1917. Serial No. 147,473.

To all whom it may concern:

Be it known that I, EDWIN H. LUDEMAN, a citizen of the United States, residing at New York, in the county of New York and State of New York, have invented certain new and useful Improvements in Steam-Heated Pistons, of which the following is a specification.

In steam engines, particularly those of the uniflow type, that is, in which exhaust ports are located about the middle of the cylinder and are controlled by the piston, the value of a steam heated piston has been demonstrated, and it is the object of the present invention to provide improved means for heating the piston, especially the faces thereof against which the steam impinges when it is let in through the inlet valves. This object may be effected by steam inlets to the piston which register with a steam supply pipe at the end of each stroke, and this may be done without the use of a hollow tail or piston rod, or other inconvenient devices.

The invention may be embodied in various forms, of which one is illustrated in the accompanying drawing; in which Figure 1 is a longitudinal section of a uniflow engine provided with the improvement. Figure 2 is a cross section on the line 2-2 of Fig. 1.

The cylinder of the engine is illustrated in the drawings at 6 and is shown provided with steam inlets 7 at opposite ends, which will be controlled by suitable valves in a known manner. About the middle of the cylinder it is provided with a double row of exhaust ports 8 which communicate with a double uniflow exhaust belt 9. There is thus produced a bridge or closed space 10 between the exhaust ports, the purpose of which is to provide a place for the opening of a steam supply pipe 11, through which live steam is supplied, from any suitable source, to the interior of the piston. The same result could be attained in other ways, the essential points being that a steam supply pipe shall open through the wall of the cylinder in such position that it may register with a port in the piston at some time, and be covered and closed by the piston at other times, and be closed off from the cylinder space at all times.

As shown, each end or head of the piston has a cored or annular chamber 12, with a port 13 located in such position that it will register with the open pipe 11 at the end of

the piston stroke, whereby steam will be admitted into the said chambers 12, with the result of heating the adjacent walls of the piston. The two end chambers may be connected by a pipe or passage 14 to distribute the steam to both chambers.

The pipe 11, and the ports 13, are preferably placed at the bottom of the cylinder where the weight of the piston holds it in close contact with the cylinder wall, whereby leak between the surfaces will be prevented. Or additional means may be used to prevent such leak, such as packing set in the wall around the ports.

For drainage, and to provide a circulation, a small drain port 16 is located near the bottom of the chambers 12 in position to register with a drain port and pipe 17, leading off from the cylinder, and this may be provided with a valve 18 to let off condensation when desired.

It will be noticed that the inlet ports 13 to the steam chambers in the piston, as well as the drain ports 16, are located on such line, or in such positions, that they will not cross the main outlet ports 8, but will pass over the bridges between the same, so that no undesirable escape of steam from the chambers will take place, and, except when registering with the corresponding pipes, all the pipes and ports will be closed against the steam in the cylinder and the exhaust, the piston being long enough to lap the pipes at the end of each stroke, one or the other set of main exhaust ports being nevertheless uncovered at the end of the stroke. The heated surfaces of the piston prevent initial condensation and otherwise assist economical and efficient operation.

The invention is not limited to the exact embodiment shown, but various modifications may be made within the scope of the following claims.

I claim:

1. The combination with a steam engine cylinder and a long hollow piston, the cylinder having inlet ports at opposite ends, and exhaust ports controlled by the piston, of a steam supply pipe having an opening through the wall of the cylinder independent of said inlet ports, the piston having a port which registers with said opening to admit steam to the interior of the piston at some time in its stroke, and which piston covers and closes the opening at all other times, said port being out of communication

with the said inlet and exhaust ports at all times.

2. The combination with a uniflow steam engine cylinder and hollow piston, the cylinder having inlet ports at opposite ends, and exhaust ports controlled by the piston and arranged at opposite sides of the middle line of the cylinder, of a steam supply pipe having an opening through the cylinder wall 10 distant from said inlet ports and between said exhaust ports, whereby the piston always laps said opening, and said piston having a port which registers with said opening at the end of its stroke, said port 15 being out of communication with said inlet and exhaust ports at all times.

3. The combination with a steam engine cylinder having exhaust ports at opposite sides of the middle line thereof, with a part 20 of the cylinder wall bridged between said ports, of a hollow piston adapted to alternately uncover said ports at the ends of opposite strokes, and which laps said bridged part at all times, and a steam supply pipe 25 opening through said bridged part, the piston having a port near its end which registers with said pipe at the end of stroke to admit steam into the piston.

4. The combination with a steam engine cylinder having exhaust ports at opposite sides of the middle line thereof, with a part 30 of the cylinder wall bridged between said ports, of a hollow piston adapted to alternately uncover said ports at the ends of opposite strokes, and which laps said bridged part at all times, and steam supply 35

and drain pipes opening through said bridged part, the piston having inlet and drain ports which register with said pipes at the end of stroke to permit steam to flow 40 through the piston.

5. The combination with a steam engine cylinder having a double row of exhaust ports with a space between bridged by the cylinder wall, and a supply pipe for heating 45 fluid opening through said bridged part, of a hollow piston adapted to alternately uncover each row of exhaust ports at the ends of opposite strokes, said piston having an inlet port to the interior thereof, said port 50 registering with said supply pipe opening at about the end of stroke and covering the same at other times.

6. The combination with a steam engine cylinder having a double row of exhaust 55 ports with a space between bridged by the cylinder wall, and a supply pipe for heating fluid opening through said bridged part, of a hollow piston adapted to alternately uncover each row of exhaust ports at the ends 60 of opposite strokes, said piston having an inlet port to the interior thereof, said port registering with said supply pipe opening at about the end of stroke and covering the same at other times, and means to drain said 65 heating fluid from the interior of the piston.

In testimony whereof, I affix my signature in presence of two witnesses.

EDWIN H. LUDEMAN.
